UNITED STATES PATENT OFFICE.

WILLIAM H. GREVER, OF BUFFALO, NEW YORK.

DESIGN FOR A FLOWER-POT COVER.

No. 38,792.

Specification for Design.

Patented Sept. 10, 1907.

Application filed May 14, 1907. Serial No. 373,677. Term of patent 7 years.

To all whom it may concern:

Be it known that I, WILLIAM H. GREVER, a citizen of the United States, residing at Buffalo, in the county of Erie and State of New York, have invented a new, original, and ornamental Design for a Flower-Pot Cover, of which the following is a specification, reference being had to the accompanying drawing, forming part thereof.

The figure is a perspective view of a flower pot cover, showing my new design.

I claim:

The ornamental design for a flower pot cover, as shown.

WILLIAM H. GREVER.
